(57) **CLAIM**

The ornamental design for an oral irrigator handle, as shown and described.

DESCRIPTION

FIG. 1 is a front isometric view of a first embodiment of an oral irrigator handle showing my new design.

FIG. 2 is a front elevation view of the oral irrigator handle of FIG. 1.

FIG. 3 is a rear elevation view of the oral irrigator handle of FIG. 1.

FIG. 4 is a right side elevation view of the oral irrigator handle of FIG. 1.

FIG. 5 is a left side elevation view of the oral irrigator handle of FIG. 1.

FIG. 6 is a top plan view of the oral irrigator handle of FIG. 1.

FIG. 7 is a bottom plan view of the oral irrigator handle FIG. 1.

FIG. 8 is a front isometric view of a second embodiment of an oral irrigator handle showing my new design.

FIG. 9 is a front elevation view of the oral irrigator handle of FIG. 8.

FIG. 10 is a rear elevation view of the oral irrigator handle of FIG. 8.

FIG. 11 is a right side elevation view of the oral irrigator handle of FIG. 8.

FIG. 12 is a left side elevation view of the oral irrigator handle of FIG. 8.

FIG. 13 is a top plan view of the oral irrigator handle of FIG. 8; and,

FIG. 14 is a bottom plan view of the oral irrigator handle FIG. 8.

The broken lines in the drawings illustrate portions of the oral irrigator that form no part of the claimed design.
